UNITED STATES PATENT OFFICE.

CHARLES B. MOORE, OF EVANSTON, ILLINOIS, ASSIGNOR TO AMERICAN ARCH COMPANY, OF NEW YORK, N. Y., A CORPORATION OF NEW YORK.

LOCOMOTIVE-BOILER FURNACE.

1,115,956.

Specification of Letters Patent.

Patented Nov. 3, 1914.

Application filed February 14, 1912. Serial No. 677,562.

To all whom it may concern:

Be it known that I, CHARLES B. MOORE, a citizen of the United States, and a resident of the city of Evanston, Cook county, Illinois, have invented certain new and useful Improvements in Locomotive-Boiler Furnaces, of which the following is a specification.

My invention relates to improvements in locomotive furnaces and has particular reference to improvements in refractory baffles or deflecting walls, commonly called arches, for the fireboxes of locomotives.

The general objects of my invention are to provide a refractory arch which can be easily and quickly installed in a locomotive firebox; to provide an arch which shall be of light weight and low cost; to provide an arch which shall be easy to repair; parts of which may be readily removed for the purpose of affording easy access to the side sheets and flue sheet of the firebox and which shall comprise interchangeable members; and to provide an arch of a form that shall materially prolong the stay of the fuel gases and suspended particles in the firebox and assist in the admixing of the firebox gases and the igniting of the gases and the fuel particles carried thereby.

A further object is to provide an improved refractory arch construction having the characteristics herein outlined which shall be particularly adapted for installation and use in locomotive fireboxes that are equipped with a plurality of water-circulating or arch-supporting tubes.

A special object of my invention is to provide a light, self-aligning and self-supporting arch structure of great strength and stability for a relatively wide span between tubes.

My invention resides in an arch having the characteristics mentioned and by which the above and other objects are attained.

My invention also consists in the several improvements, the various constructions and the combinations of parts hereinafter described and particularly pointed out in the appended claims.

In the accompanying drawings, forming a part of this specification, and illustrating a preferred embodiment of my invention; Figure 1 is a vertical, central, longitudinal section of a locomotive firebox equipped with a wide span refractory arch or baffle embodying my invention; Fig. 2 is a hori-

zontal sectional view of the fire-box on the line 2—2 of Fig. 1 and shows a top view of the arch; Fig. 3 is a transverse vertical sectional view of the fire-box on the line 3—3 of Fig. 1 and shows an end view of the arch; Fig. 4 is a transverse fragmentary sectional view of the firebox and arch at right angles to the arch tubes on the line 4—4 of Fig. 1; Fig. 5 is a transverse fragmentary sectional view of the firebox and arch at right angles to the arch tubes on the line 5—5 of Fig. 1; Fig. 6 is an enlarged perspective view of one of the complementary arch span or alining bricks; Fig. 7 is an enlarged perspective view of one of the tube-abutting arch panel bricks; and Fig. 8 is a vertical, longitudinal sectional view of the refractory arch on the line 8 of Fig. 2.

My invention may be embodied in arches occupying various positions in the firebox and having different specific functions. I have, however, confined the illustration of the invention to so-called front arches, but I wish it to be understood that my invention is not limited to this specific form of arch.

A so-called front arch usually occupies an inclined position in the firebox extending substantially from side to side therein and having its forward end in substantial abutment with the flue sheet. The principal function of these arches is to deflect the firebox gases out of their direct line of flow from the grate to the flues and to cause them to travel back and forth in the firebox thereby not only distributing their heat to substantially the whole interior surface of the firebox, and especially throughout the length of the crown sheet, but also serving to admix or commingle the various strata of gases and thereby assist in the complete combustion of the fuel. A second result accomplished by the deflection of the gases is that they are retained thereby in the firebox long enough to accomplish their complete combustion before they escape through the flues.

Front arches constructed in accordance with my invention not only perform the functions above mentioned, but also by reason of their comparative thinness so as to attain substantially the maximum temperature of the firebox gases and thereby assist in the ignition of the oncoming gases and fuel particles carried by said gases.

A locomotive firebox, as illustrated in the drawings, is made up of a flue sheet 2, side sheets 3—3, a crown sheet 4 and a rear sheet 5. The firebox has a grate 6 and the rear sheet is provided with a fuel doorway 7. Flues 8 lead forward from the flue sheet.

The fire box, illustrated, is equipped with two arch or water circulating tubes 9, the same extending from the lower portion of the flue sheet to the upper portion of the rear sheet and serving to increase the circulation of water between the front and rear water legs of the firebox. It is readily apparent that in case more than two tubes are used in a wide firebox, two or more identical arched structures may be provided, one between each adjacent pair of tubes making a substantially continuous arch.

My invention is characterized by the feature that my improved arch is built up of one or more transversely arranged self-supporting rows of panel bricks, said rows being of inverted V shape and resting wedgingly against the arch tubes at the sides of the arch proper, and said bricks abutting one another intermediately of the tubes, the individual bricks of each transverse row being held in mutual wedging or arched alignment by means of transversely positioned complementary span or alining bricks arranged like an inverted V and wedgingly abutting against the arch tubes at their lower ends. When the bricks are placed in position on the tubes they are mutually locked or held together by gravity, but the arch being made up of a plurality of brick members which do not become readily cemented together, not only permits the easy replacement of members which become damaged or worn out, but it is, in a sense, flexible enough to accommodate itself to changes of shape and dimensions of the firebox due to expansion and contraction, and hence it is protected against the disintegration which affects solid arches from this cause.

The size of the bricks, other than that they must be long enough when duly fitted together to form an arch spanning the space between the tubes, are preferably formed as large as possible without being too large or heavy to handle conveniently, and without being too large to be passed readily through the firebox doorway.

In the embodiment of my invention herein illustrated, alining bricks A, in complementary pairs, are placed transversely of and in arched or wedging position in an inverted V-shape on the tubes 9, the several pairs being held in spaced relation longitudinally of the tubes by the panel bricks B which constitute the main body of the arch. Steadyng bricks C are arranged side by side in the relatively narrow space between the side sheets and the tubes or arch proper.

These bricks C are inclined in wedging position to securely lock the arch against lateral swinging or destructive vibration, such as otherwise would often be caused to a considerable extent by the motion and jar of the locomotive when in use.

The alining bricks or arch spans A are made very light, being relatively long and narrow or slender, but deep and strong enough to answer their purpose. The outer or lower end of each has a transverse groove A' to fit and rest upon the adjacent arch tube, while the inner or upper end is provided with a half tongue A² and a half groove A³ formed to fit a corresponding tongue and groove on the adjacent similar end of the abutting span brick and adapted to hold these complementary bricks in rigid coacting or abutting relation to aline the panel bricks B and maintain them in mutual arched relation. The said tongues and grooves are preferably arranged parallel to the tube-engaging grooves on the opposite ends. The upper lateral edges or corners of the alining bricks or arch spans A are provided with gains A⁴ to accommodate the ends of the panel or cover bricks B which are held in alinement thereby.

Each of the panel or cover bricks B comprises a relatively thin rectangular top or web portion B' and a substantially perimetrical depending flange B² extending around the underside adjacent to the edges. The flange B² serves to brace and strengthen the panel or cover and forms and contains a downwardly facing pocket B³ on the underside of the panel or cover adapted for retarding and mixing the firebox gases. The part of flange B² which extends along the edges adjacent to the alining bricks or arch spans A is slightly removed from the extreme end, thus providing on each end a projecting bearing-shoulder or flange B⁴ adapted to fit into and rest upon the ledge or gain A⁴ of the alining brick or arch span A. The part of flange B² which extends along the other two sides is flush with the edges and serves as abutting means to bear the chief part of the wedging or arch pressure of the self-supporting panel or cover members B against each other. The flange B⁴ on the tube-engaging side of each of those panels or covers which are adjacent to a tube is provided with a groove B⁵ adapted to fit against said tube. The flange along the adjacent edges of the center or ridge forming panel or cover bricks is preferably beveled to accommodate the angular relative position of the bricks and to provide a reasonably close fit. The longitudinally extending top edges of the panel or cover bricks B are beveled as at B⁶ to prevent adjacent bricks from being fused together or held by slag. Even in case they stick together on the underside it is in easy matter

to insert a wedge in the grooves B^7 formed by the beveled edges and split them apart.

The wedging locking or sheet-engaging bricks C are preferably similar in general form and construction to the panel bricks B . It is chiefly necessary that they shall be of such length as to substantially cover the space longitudinally at the side of the arch proper and that they shall be of such width that when the inner edge rests on the tube the brick shall incline upwardly against the side sheet in a wedging position to securely lock the arch against lateral vibration. The lower edge is provided with a groove C^2 to fit the tube 9 . A gas-mixing pocket C^2 surrounded by the depending flange C^2 is provided on the underside of the brick.

My improved arch readily adapts itself to different fireboxes in which the arch tubes are spaced at various distances within ordinary practical limits, the wider the tubes are apart the flatter being the arch and vice versa.

To construct my improved arch, I first place a pair of alining bricks or arch spans in their arched or wedging position adjacent to the flue sheet with the grooved bearing ends resting upon the tubes and with the tongued and grooved ends fitted together. I then place a second pair of alining bricks or arch spans in position at a suitable distance from the first pair, whereupon a row of panel bricks may be placed in mutually wedging or arched position on the tubes between the alining bricks or arch spans with the ends or flanges B^7 of the panel bricks fitting in the gains A^4 of the alining bricks. Each side or leg of the inverted V-shaped arch contains a plurality of the said panel bricks of each row thereof. One row of panel bricks may suffice, but it is usually preferably to add sufficient rows to bring the upper or rear edge of the arch to approximately the center of the firebox. Ordinarily two rows of panel bricks and three pairs of alining bricks or arch spans serve the desired purpose, as illustrated by the drawings. I thus build an arch which consists of complementary pairs of alining arch spans or bricks A which hold in alinement complementary inclined roof members or panel arch spans consisting of the panel or cover bricks B , each inclined roof member or panel arch span being held in alinement by two complementary pairs of alining arch spans or bricks.

It is well known that bricks generally and especially fire bricks have great strength to resist compression but are easily broken by transverse or bending forces. Hence by my improved arch structure, in which the forces are chiefly compression, the bricks may be made light and thin. The panel bricks being light and thin would tend to gradually work out of alinement under the influence

of vibration caused by the operation of the locomotive, but this is prevented by the alining bricks or arch spans which are definitely interlocked at their abutting ends and engage the adjacent ends of the panels.

The arched arrangement of all of the bricks enables mutual self support as long as they are held in alinement. As the panel bricks are substantially self supporting the alining bricks or arch spans need little more than to be thick and strong enough to be self supporting for when strong enough for this they are rigid and strong enough to withstand the slight tendency of the panels to jar out of alinement. The bricks even when worn so thin along their central portion as to have very little bending or transverse strength are held by their compression strength in arched position in the structure.

As many modifications of my invention will readily occur to those who are skilled in the art, I do not wish to limit my invention to the specific structures herein shown and described.

Having thus described my invention I claim as new and desire to secure by Letters Patent:

1. A locomotive boiler firebox having a pair of arch tubes spaced widely apart therein, in combination with a refractory arch supported by said tubes and comprising a transverse row of arch panel bricks abutting each other end to end and resting wedgingly upon and between said tubes, and a pair of substantially identical alining bricks in arched position at each side of said row of panel bricks and resting on said tubes, said alining bricks and said panel bricks being formed on their adjacent edges to mutually engage each other, the alining bricks holding the panel bricks in self-supporting or wedging alinement.

2. A locomotive boiler firebox having a pair of arch tubes spaced widely apart therein, in combination with a refractory arch supported by said tubes and comprising a pair of alining arch spans suitably spaced apart longitudinally of and resting on the tubes and each consisting of two oppositely inclined mutually supporting alining bricks and an arched span each side thereof composed of a plurality of panel bricks resting on said tubes and lying between said alining spans and held in alinement therby.

3. A locomotive boiler firebox having a pair of arch tubes spaced widely apart therein, in combination with a refractory arch supported by said tubes and comprising a pair of alining arched spans suitably spaced apart longitudinally of and resting on the tubes and a panel arched span resting on said tubes and lying between said alining spans and held in alinement thereby, each of said arch spans comprising a

pair of relatively long narrow bricks grooved on their outer ends to fit the tubes and tongued and grooved at their inner or meeting ends to hold the said alining 5 bricks in fixed relative position.

4. A locomotive boiler firebox having a pair of arch tubes spaced widely apart therein, in combination with a refractory arch supported by said tubes and comprising 10 a pair of alining arched spans suitably spaced apart longitudinally of and resting on the tubes and a panel arched span each side thereof consisting of a plurality of alined abutting bricks and which rests on 15 said tubes and lies between said alining spans and is held in alinement thereby, each of said panel bricks being formed to fit squarely against its neighbor and those at the ends being grooved to fit the supporting 20 tubes.

5. A locomotive boiler firebox having inclined arch tubes therein, in combination with a refractory front arch resting on and supported by said tubes and comprising a 25 plurality of similar transverse rows of substantially identical panel or cover bricks each row consisting of a V-shaped arch span, each side of which contains more than one brick and which rests wedgingly 30 on and between said tubes, and transverse alining members extending along the edges of said rows of panel bricks and engaging the latter to hold them in alinement.

6. A locomotive boiler firebox containing 35 a plurality of longitudinally extending, widely spaced and substantially parallel inclined arch tubes, in combination with a refractory front arch therein arranged against the flue sheet and co-extensive 40 transversely of the firebox with the said arch tubes, said arch comprising a transversely extending row of panel or cover bricks arranged in V-shaped wedging or arched relation upon and between said 45 tubes, and alining members arranged in similar V-shaped or arched pairs and comprising complementary interlocking elements resting upon and extending between

said tubes at the side of and in engagement with the edges of said row of panel bricks 50 to hold same in compressive alinement.

7. A locomotive boiler firebox containing a plurality of longitudinally extending, widely spaced and substantially parallel inclined arch tubes, in combination with a 55 refractory front arch therein arranged against the flue sheet and co-extensive transversely of the firebox with the said arch tubes, said arch comprising a plurality of light pairs of slender alining members 60 suitably spaced apart longitudinally in the firebox and extending from tube to tube and arranged in mutually supporting arched relation, and a row of light, thin panel bricks arranged between adjacent 65 pairs of alining bricks resting on the tubes and comprising a plurality of panel bricks arranged between adjacent longitudinally spaced alining members and held in alined position thereby, whereby the rows of panel 70 bricks are substantially self-supporting.

8. A locomotive boiler firebox having a pair of arch tubes spaced widely apart therein, in combination with a refractory arch resting wedgingly upon and between 75 said tubes, and wedging locking bricks arranged between the said tubes and the adjacent side sheets of the firebox to prevent the spreading of the tubes due to the wedging action of the arch, said arch comprising 80 a series of panel bricks arranged end to end and abutting one another in arched or wedging position and extending from tube to tube and rigid alining members lying adjacent to the front and rear edges of said 85 panel bricks and maintaining them in self-sustaining arched or wedging alinement.

In testimony whereof, I have hereunto set my hand, this 24th day of January, 1912, in the presence of two subscribing 90 witnesses.

CHARLES B. MOORE.
